CLAIM

The ornamental design for a white noise and sleep aid device in combination with a plush toy having an elephant-like appearance, as shown and described.

DESCRIPTION

FIG. 1 is a front view of the herein disclosed white noise and sleep aid device in combination with a plush toy having an elephant-like appearance, illustrating the present design;

FIG. 2 is a rear view of the herein disclosed white noise and sleep aid device in combination with a plush toy having an elephant-like appearance, illustrating the present design;

FIG. 3 is a side view of the herein disclosed white noise and sleep aid device in combination with a plush toy having an elephant-like appearance, illustrating the present design;

FIG. 4 is a top-down view of the herein disclosed white noise and sleep aid device in combination with a plush toy having an elephant-like appearance, illustrating the present design; and,

FIG. 5 is a bottom-up view of the herein disclosed white noise and sleep aid device in combination with a plush toy having an elephant-like appearance, illustrating the present design.

The broken lines shown in the various figures are for illustrative purposes only and form no part of the claimed design.

1 Claim, 5 Drawing Sheets
